SINGLE SIDEBAND TRANSMITTER

Leonard R. Kahn, New York, N. Y., assignor to
 Radio Corporation of America, a corporation
 of Delaware

Application August 16, 1951, Serial No. 242,061

26 Claims. (Cl. 250—17)

1

This invention relates to transmitters, and more particularly to single sideband (SSB) transmitters.

The present application is a continuation-in-part of my copending applications, Serial No. 90,243, filed April 28, 1949, and Serial No. 162,757, filed May 18, 1950, both of which are now abandoned.

In comparing single sideband carrier suppressed systems and double sideband systems, a gain in signal-to-noise ratio of 9 db has been reported for single sideband systems over double sideband systems. It is known that single sideband systems have other advantages such as more effective or more efficient use of the frequency spectrum. The main disadvantage of a conventional single sideband system is the complex and costly equipment which must be used.

The intelligence in a single sideband signal is transmitted by varying two properties of the transmitted wave, namely the amplitude and the phase. The phase variations carry a large number of sidebands with distinct bundles of energy; the amplitude modulation determines the total energy given to the entire signal at any instant of time, and also neutralizes some of the sidebands and reinforces others. In order to pass the amplitude modulation characteristic of the single sideband signal, the conventional single sideband transmitters must have all stages that amplify the single sideband radio frequency signal adjusted for linear operation.

Linear radio frequency amplifiers are difficult to design, are rather expensive and complex, and are relatively inefficient. Further, linear amplifiers are difficult circuits to adjust, as a result of which difficulties arise in maintenance during normal transmitter operation or when changes are to be made in the tuning of the transmitter.

An object of this invention therefore is to eliminate the necessity of using linear amplifiers on all the radio frequency stages of a single sideband transmitter.

Another object is to devise a system by means of which amplifiers of higher efficiency, of less cost, and of relative simplicity, may be used in a single sideband transmitter.

An additional object is to provide an arrangement by means of which class C amplifiers may be used in a single sideband transmitter; amplifiers of this type are rather easy to adjust.

A further object of this invention is to make possible easy modification of existing double sideband amplitude modulated transmitters for sin-

2

gle sideband service, thus permitting the use of high level amplitude modulation techniques in single sideband transmitters without the need for high level linear amplifiers.

5 In the conventional single sideband transmitters, which use a large number of linear amplifier stages, difficulties arise when it is attempted to use negative feedback in order to effect a reduction in distortion in such stages. In such 10 transmitters, positive feedback often occurs. This is undesired because such positive feedback sets up oscillations. In the system of this invention in which the number of linear amplifier stages is greatly reduced as compared to conventional systems, the possibility of positive feedback is reduced; therefore, negative feedback may be utilized more dependably in the system of this invention than in conventional single sideband systems.

15 It is well known that certain difficulties arise if all stages of a transmitter operate at the same frequency. Such operation at the same frequency may be termed "straight frequency operation." If straight frequency operation is utilized, there is a strong tendency toward regeneration. 20 Such regeneration or "singing" is undesirable. The tendency toward regeneration may be reduced by careful shielding. Such shielding, however, is expensive and therefore rather impractical.

25 Most transmitters employ frequency multiplication to reduce the shielding otherwise necessary. There is much less chance of regeneration if the entire transmitter does not operate at the same frequency.

30 The present application discloses a system which allows frequency multiplication to be utilized in a single sideband transmitter, so that all stages of the transmitter do not have to operate at the same frequency.

35 Although the present invention will be described in connection with the amplification of single sideband signals, it is equally applicable to the amplification of other forms of hybrid modulated waves. A "hybrid modulated wave" may be defined as one which has both amplitude and angular velocity modulation components. Examples of hybrid modulated waves are: carrier suppressed double sideband, single sideband, vestigial sideband, and quadrature modulated waves.

40 The foregoing and other objects and advantages of the invention will be best understood from the following detailed description thereof,

reference being had to the accompanying drawings, wherein:

Figs. 1-4 are diagrams of various types useful in explaining the invention;

Fig. 5 is a block diagram of a single sideband transmitter according to the present invention;

Fig. 6 is a partial block diagram of a modification; and

Figs. 7A, 7B and 7C taken together constitute a detailed circuit diagram of the essential elements of a transmitter according to this invention.

Briefly, the objects of this invention are accomplished in the following manner: A portion of the single sideband wave to be amplified is passed through several stages of limiters, thereby eliminating the amplitude modulation component and producing the pure phase modulation component. This phase modulated wave is divided in frequency, amplified by highly efficient, non-critical class C amplifiers, heterodyned to a higher frequency, multiplied in frequency and finally amplified to the desired output level, again by class C amplifiers. The original single sideband wave amplitude modulation envelope is detected and the resultant audio frequency wave is amplified in an audio amplifier and then passed through an amplitude equalizer and a delay network. The amplified detected amplitude modulation envelope then remodulates, in a power amplifier, the amplified phase modulation component, resulting in an amplified copy of the original single sideband wave. If the phase and amplitude modulation components are recombined in proper phase and with proper amplitudes, the undesired sidebands of the phase and amplitude modulation components will cancel, reproducing the single sideband wave form. For any form of intelligence transmission such as voice, in which the amount of energy transmitted in a given period of time may vary, the unidirectional component of the amplitude modulation component is utilized to correspondingly vary the average output power of the transmitter.

Before describing the transmitter or amplifying system of this invention in detail, it may prove helpful to review the characteristics of a single sideband wave. Fig. 1 shows the spectral distribution of a single sideband wave having equal carrier and sideband amplitudes. The upper sideband is represented in this figure and it represents a signal frequency of 600 cycles, so that F_S is 600 cycles higher than F_C on the frequency axis.

Fig. 2 is a vector representation of the single sideband wave represented in Fig. 1. The carrier frequency is the reference vector. Thus, the sideband vector revolves past the reference vector at a velocity corresponding to the tonal frequency of the signal, which in our example is 600 cycles. If one considers the resultant of the sideband and carrier vectors, it may be seen that such resultant will vary both in amplitude and angular velocity. Therefore, a single sideband wave has both amplitude and phase modulation components.

Fig. 3 is a representation of the amplitude modulation envelope of the single sideband wave, or the amplitude modulation component of such wave. This envelope has a wave shape which is identical with the shape of the wave derived from a full-wave resistance-loaded rectifier fed with a sine wave input.

Fig. 4 shows the phase modulated component

of a single-sideband signal having equal carrier and sideband amplitudes. It is seen, that even though a single sideband transmitter is modulated by pure tone the phase modulation wave shape is not necessarily sinusoidal.

In Fig. 3, it is shown that the amplitude modulation component having signal tone modulation is also not necessarily sinusoidal.

Recently Villard, in an article entitled "Composite Amplitude and Phase Modulation" in the November 1948 issue of "Electronics," pages 86-89, described a transmitter which uses a fairly well-known system of single sideband generation. This system uses independent phase and amplitude modulators to produce a single-sideband signal. Since a pure amplitude modulator produces a sinusoidal envelope shape when a single tone is applied and a phase modulator produces a sinusoidal phase modulation component when a single tone is applied, this system is not capable of generating the wave forms required, which were shown in Figs. 3 and 4. Therefore, a large amount of distortion is to be expected and this distortion was reported by Villard. Another problem associated with this form of single sideband transmitter is that it is not possible to suppress the carrier to any great extent. Therefore, the saving in power common to suppressed carrier operation is not obtained in this system.

The subject invention is theoretically capable of producing undistorted signals. The only limitation as to the quality of the system is the goodness of the equipment.

Similarly, if two single sideband tones, of frequencies A and B, are combined, a resultant wave varying in amplitude and phase at the difference frequency, $A-B$, will be produced. Only if one of the tones is substantially larger than the other will the resultant amplitude and phase modulation be essentially sinusoidal.

Fig. 5 is a block diagram of a system according to this invention which was actually constructed and tested. A single sideband generator 1 has a modulating signal of any desired type applied to its input. For example, such modulating signal input may consist of two or more multiplexed audio tones, each of which is shifted in frequency in accordance with the intelligence in the corresponding multiplex channel. The generator 1 produces single sideband tone frequencies from the input audio tones and may consist of one or more balanced modulators supplied with the audio input tones and also with locally-generated wave energy, and in addition bandpass filters for selecting one or the other of the sidebands produced in the modulators. If the upper sideband is selected in generator 1, the output frequency of the generator may be, for example, 150 kc. plus audio tone frequencies.

For simplification, let us consider the case in which a single tone is fed to the input of generator 1 and let us assume that this tone produces a sideband equal in amplitude to the carrier. Generator 1 produces a low-power single sideband signal identical with that depicted in Figs. 1, 2, 3 and 4.

The low-power single sideband signal output of generator 1 is fed through a linear radio frequency amplifier 2 the output of which is fed to two separate channels, the first of which may be termed the phase modulation channel and the other, the amplitude modulation channel. The first or phase modulation channel begins with a limiter 3 to which is fed the amplified single sideband sig-

hal output of amplifier 2. Limiter 3 is preferably a full-wave, biased germanium diode clipper-limiter of the shunt-connected type.

The limited output of limiter 3 is applied to an amplifier 4. This amplifier may be either linear or non-linear, but is preferably non-linear or class B, in order to improve its efficiency and reduce the cost of the system. The output of amplifier 4 is fed to a second limiter stage 5, which is preferably exactly similar in construction to limiter 3.

The limiters 3 and 5 operate to limit the single sideband signal applied thereto, removing substantially all the amplitude modulation component from such signal, such component not being removed, of course, where the amplitude of the input tone or tones goes through zero. Therefore, the output of limiter 5 contains substantially only the phase modulation component of the original single sideband signal, so that such output is a substantially pure phase modulated wave.

The wave output of limiter 5, the envelope of which may be substantially flat-topped or square, is passed through a wide band linear amplifier 6, which must be wide band in order to faithfully pass the flat-topped or square wave limiter output.

There are side-frequency components generated in a phase modulated or frequency modulated generator. Therefore, such components appear in the output of generator 1, since such output has in effect a phase modulated component. The number and amplitudes of these side-frequency components depend on the phase modulation index of generator 1. According to this invention, the amplitude modulated component and the angular or phase modulated component are both derived from the single sideband output signal of generator 1. The amplitude variations in the amplitude modulation component channel, to be later described, include components that are utilized in cancelling the undesired Bessel sidebands. These components should have the proper magnitude and phase to cancel the undesired sidebands of the phase modulation component channel.

As previously discussed, it is desirable that frequency multiplication be used in the transmitter in order to eliminate the shielding that is quite essential in straight frequency operation. If the phase modulation component signal at the output of amplifier 6 were passed through the frequency multipliers in the transmitter without first being divided in frequency, the modulation index applicable to the phase modulation component signal at the output side of such multipliers would be different from that existing at the output of generator 1, since in such multipliers the deviation or phase shift is increased. In fact, the applicable modulation index at the multipliers' output would be higher than that at the output of generator 1; thus, a larger number of side-frequency components, and components of different amplitudes, would be produced at the multipliers' output, as compared to those present at the output of generator 1. In such event, since the amplitude variation balancing components are derived from the output of generator 1, the undesired Bessel phase modulated sidebands would no longer be balanced out of the phase modulation component channel.

Two cascaded frequency dividers 7 and 8, having a total division factor of n , are provided prior to the frequency multipliers in the transmitter, which have a multiplication factor of n . In this way, the modulation index applicable to the out-

put of generator 1 is first divided by n and later multiplied by n . This results in no net change in the modulation index applicable to the multiplier output, as compared with such index applicable to the output of generator 1. Therefore, the modulation index applicable to the multiplier output is made such as to enable balancing out of the undesired phase modulation component sidebands. In other words, the phase modulation components are preserved at the transmitter output frequency. At the same time, the reduced chances of regeneration provided by frequency multiplication are retained.

In a typical example of this invention, the factor n has a value of four, so that a division factor of four is used in the frequency dividers and a multiplication factor of four is used in the transmitter frequency multipliers. Frequency divider 7 is coupled to the output of amplifier 6 and has a division factor of two, while frequency divider 8 is coupled to the output of divider 7 and also has a division factor of two, so that a division factor of four is provided by dividers 7 and 8. Divider 7 and divider 8 may each comprise a flip-flop counter-type circuit having a differentiating circuit in its input. Continuing with the typical example, if the single sideband signal out of generator 1 has a frequency of 150 kc., then the output of divider 8 will be at 37.5 kc.

30 The phase modulation component of the single sideband signal is divided in frequency by a factor of four in dividers 7 and 8. The output of divider 8 is a phase modulated signal which can be conveniently amplified by highly efficient class C amplifiers without the introduction of any distortion. The output of divider 8, which is stated above may have a mean frequency of 37.5 kc., for example, is fed through a class C amplifier 9 to a bandpass filter 10 which removes harmonics of the 37.5 kc. frequency. Filter 10, may, for example, pass a band 10 kc. wide, centered on 37.5 kc.

Following the passage of the wave through filter 10, the frequency of the phase modulation component of the single sideband signal is converted to that used to drive the lower level multiplier stages of the transmitter, which in our example would be one-fourth of the output frequency. This frequency conversion is effected in two stages, the first being from 37.5 kc. to 250 kc. For this stage of the conversion, the 37.5-kc. output of filter 10 is fed to a balanced modulator 11, to which is also fed heterodyning energy of 212.5 kc. from a crystal oscillator 12. For example, the modulator 11 may comprise a pair of pentagrid converter tubes connected in a push-pull arrangement, the 37.5-kc. frequency being fed antiphase to one grid in each of the two tubes and the 212.5-kc. frequency from oscillator 12 being fed cophasally to another grid in each of the two tubes. The output of modulator 11 may have a frequency band of 250 ± 5 kc.

The 250-kc. output of modulator 11 is amplified in a class B radio frequency amplifier 13 and is then passed on to the second frequency conversion stage, wherein the phase modulation component is converted from 250 kc. to the frequency for driving the transmitter multiplier stages, which latter frequency is 1750 kc. in our example. The 250-kc. output of amplifier 13 is fed to a balanced modulator 14, to which is also fed heterodyning energy of 1500 kc. from a high frequency crystal oscillator 15. The modulator 14 is preferably exactly similar in arrangement to modulator 11, previously described. The output

of modulator 14 may have a frequency of 1750 kc.

The 1750-kc. output of modulator 14 is amplified in a class C radio frequency amplifier 16 and it is the output of this amplifier which is used to drive the lower level multiplier stages of the transmitter. The output of amplifier 16 may be used as the input to a standard amplitude modulated phone transmitter which is more or less conventional with applicant's assignee and which includes a plurality of class C multiplying and amplifying stages in the radio frequency section thereof. Utilizing this invention, the transmitter can be tuned in the normal manner and the transmitter stages can be operated in the usual manner as class C multipliers and amplifiers. In our example, n has a value of four, so that a fixed multiplication factor of four is used in the transmitter. The output of amplifier 16 is fed to a frequency multiplier 17 having a multiplication factor of four, for example. The output of frequency multiplier 17 is a phase modulated wave having a mean frequency of 4×1750 kc., or 7 mc.

The 7-mc. output of multiplier 17 is amplified to a high level in a class C radio frequency amplifier 18, which may consist of a plurality of stages. Since high power radio frequency amplifier 18 is not required to pass or amplify the amplitude modulation component of the single sideband signal, but instead only the phase modulation component of such signal, this amplifier (and also the multiplier stages in 17) need not be linear and in fact can be of the type known as class C. The use of linear amplifiers for all the high power radio frequency stages of the transmitter has by this invention been made unnecessary, thus enabling the use of less expensive and more efficient amplifiers.

This completes the description of what has been termed herein the phase modulation channel. The other or second channel, the amplitude modulation channel, will now be described.

The single sideband signal output of amplifier 2 is fed to the amplitude modulation detector 19, which is preferably of the diode vacuum tube type. This linear detector functions to rectify the single sideband wave and to remove the audio envelope therefrom, thus isolating the amplitude modulation component from the phase modulation component of the single sideband wave. The output of detector 19 corresponds to the envelope wave shape of the single sideband wave at the output of generator 1 and therefore the wave shape at such detector output is similar to that of a full-wave rectified sine wave.

The audio frequency envelope of the single sideband wave is amplified by the linear audio amplifier 20, which is coupled to the output of detector 19. Amplifier 20 must be linear since it is required to amplify faithfully the amplitude modulation envelope. This amplified audio envelope is fed through an amplitude equalizer 21 to a delay network 22. Equalizer 21 is an impedance network which can be set by means of switches to provide deemphasis and/or preemphasis correction, to compensate for any non-uniformity of the frequency characteristic of the modulator or power amplifier to be later referred to. Delay network 22 may be adjusted to provide various values of time delay for the signal passing therethrough and operates to equalize the time delays in the two channels, the phase modulation and amplitude modulation channels.

The output of network 22 is supplied to the input of the high level amplitude modulator 23

to furnish driving power therefor. Modulator 23 amplitude modulates at a high level the phase modulation signal component, derived from the output of amplifier 18, in the modulated power amplifier 24. The envelope wave shape (amplitude modulation component of the SSB signal) of the signal at the output side of modulator 23 is the same as the envelope wave shape at the output side of generator 1. Furthermore, the phase modulation component at the output side of amplifier 18 is identical with the phase modulation component at the output of generator 1. If the time relationships between the phase and amplitude modulation components are properly maintained, the signal at the output of amplifier 24 will be a pure, high-power single sideband wave. More in particular, when the delay network 22 is correctly adjusted to equalize the time delays in the two channels and when the amplitude equalizer 21 is properly adjusted to give the proper amplitude of audio wave as applied to modulator 23, the amplitude modulation and phase modulation components retain the original phase relationship of the single sideband wave; under these conditions, sufficient high level amplitude modulation is effected in 24 to reproduce the form of the original SSB signal, thus cancelling the spurious sidebands introduced when the signal is split into its two components.

The signal at the output of power amplifier 24, which as stated is a pure, high-power single sideband wave, may be transmitted by a suitable transmitting antenna 25 which is coupled to the output of amplifier 24. In our illustrative example, this is a single sideband signal having a nominal frequency of 7 mc., the frequency of the input to amplifier 18.

Although the delay network 22 is illustrated as being in the amplitude modulation channel, it is desired to be pointed out that it could instead be placed in the phase modulation channel if necessary, since the purpose of this network is to equalize the time delays of the signals in the two channels. Therefore, if the signal time delay in the amplitude modulation channel is greater than that in the phase modulation channel, the delay network 22 would be inserted somewhere in the phase modulation channel.

It is quite often desirable to transmit a suppressed carrier along with the single sideband signal. For this purpose, a crystal-controlled carrier frequency, of relatively low amplitude or power level, may be supplied to amplifier 24, to be radiated from antenna 25 along with the single sideband signal.

The system of Fig. 5 will operate in an optimum manner when the average signal energy to be transmitted is constant over a certain interval of time, say 0.1 second or more. Frequency-shifted frequency division multiplex signals are in this constant-average-amplitude category and can be effectively transmitted by the system of Fig. 5. However, if the average level of the amplitude modulation varies the spurious sidebands will not remain balanced at the output of amplifier 24 and the Fig. 5 system will not work in an optimum fashion. For example, voice waves are not of constant average amplitude and an additional circuit is required in Fig. 5 for transmission of this form of intelligence. Also, this varying-average-amplitude condition comes into play in certain cases with frequency shift tones. For example, assume that two equal-amplitude tones are being transmitted at a fixed input level and that the amplitude level is adjusted to bal-

ance out the spurious sidebands at the output of amplifier 24. Then, if the input level of both tones is reduced to half its previous value, the relative level of the phase modulation component would remain the same but the amplitude modulation component would have to be increased to two times its former level, or increased by 6 db, to maintain the balance for cancelling out the spurious sidebands. Similarly, if a number of frequency shift tones were transmitted at a fixed level and the average level of amplitude modulation envelope varies, the balance of the spurious sidebands would also vary.

Fig. 6 illustrates a circuit arrangement which can replace that portion of Fig. 5 shown within the dotted line box B. In Fig. 6 there is an additional circuit which is necessary for effective transmission of varying-average-amplitude signals by the transmitter of this invention. Such circuit is an output level control 26 which is used to vary the average output power of the transmitter by controlling one of the electrode voltages of power amplifier 24. Level control circuit 26 takes the form of a series of direct current amplifiers supplied with direct current output from amplitude modulation detector 19, such direct current output corresponding to the average amplitude of the input intelligence. The amplified output from unit 26 controls one of the electrode voltages of the modulated power amplifier 24. One possible method of controlling such one electrode voltage would be the varying of the firing angle of the thyratron rectifiers in the power supply for such one electrode.

To give an example of the operation of level control 26, if the carrier is suppressed 20 db for the single sideband carrier-suppressed system and there is no one speaking on the circuit, the direct current output of the amplitude modulation detector 19 will be very low; in this case, the output level control 26 will make the modulated amplifier 24 give low output. On the other hand, if voice appears on the circuit, the direct current output of detector 19 will increase and output level control 26 will cause modulated amplifier 24 to give increased output. In a similar manner, all levels of input signal energy will appear in true single sideband form at the output of amplifier 24.

In order to maintain good spurious sideband suppression, it is necessary that the modulator 23 have certain characteristics.

For a transmitter having distortion suppression to the point where all spurious output is 35 db or more below the signal output of the transmitter, the modulator 23 must be able to pass the second and third harmonics of the difference between the highest frequency and lowest frequency signals which have appreciable energy. For 25 db spurious output suppression, only the second harmonic is required to be passed.

For example, assume that it is desired to transmit the following tone frequencies: 1105, 1275, 1445, 1615, 1785, 1955, 2125, and 2295 cycles. Tones of these values could be used to provide a four-channel frequency shift frequency division multiplex signal. The highest frequency difference between large-amplitude signal components is 1190 cycles (2295 minus 1105). The carrier amplitude is normally quite small and therefore does not enter into the calculations. If a signal having 25 db suppression of spurious output is required, the modulator 23 must be equalized for phase and amplitude characteristics from at least 170 cycles to 2380 cycles (170 cycles being the smallest difference frequency between tones and 2380 cycles

being two times the highest frequency difference). If 35 db spurious suppression is required, a modulator having the proper phase and frequency characteristics from 170 cycles to 3570 cycles (3570 cycles being three times the highest frequency difference) must be used.

If telephone service (3 kc. fidelity) is contemplated, it might be expected that a maximum spurious output of -25 db would require a modulator capable of being equalized for phase and frequency from 100 cycles to 6 kc. (two times 3 kc.). However, when the characteristics of speech were analyzed, it was found that the higher frequencies have very low energy content and, therefore, do not create appreciable high energy spurious output. It may be seen from this qualitative examination that phone service may require even less stringent modulator performance than does regular tone telegraph.

With regard to the transmitter of this invention, the spurious sidebands may be balanced out to a level 30 to 40 db below the level of one tone, when two tones are used for modulation. It is a reasonable estimate that a balance of 30 db below the level of one tone, for two-tone modulation, can be maintained in practice, in a transmitter constructed according to the teachings of this invention.

Figs. 7A, 7B and 7C taken together provide a detailed circuit diagram of the essential portions of the transmitter of this invention—to wit, all of the units in Fig. 5 except SSB generator 1, frequency multiplier 17, amplifier 18, modulator 23, power amplifier 24 and antenna 25. From a study of these figures, together with the legends thereon, the interrelation of these three figures, as well as the mode of operation of the circuits disclosed therein, will become apparent.

What is claimed is:

1. In a transmitter, means for producing a single sideband signal in the form of a complex wave from a source of intelligence, said single sideband wave having amplitude modulation and phase modulation components, means for amplifying substantially only said phase modulation component, means for amplifying only the amplitude modulation envelope of said single sideband complex wave, and means for combining the amplified modulation envelope with the amplified phase modulation component to provide a resultant amplitude modulated and phase modulated wave representative of said single sideband complex wave.
2. In a transmitter, means for generating a single sideband signal, means for amplifying substantially only the phase modulation component of said signal, separate means for linearly amplifying only the amplitude modulation envelope of said signal, and means for combining the amplified modulation envelope with the amplified phase modulation component to provide a resultant amplitude modulated and phase modulated wave representative of the original single sideband signal.
3. In a transmitter, means for generating a complex wave which is amplitude modulated and phase modulated by intelligence to be transmitted, means for substantially eliminating amplitude variations from said complex wave to provide a resultant phase modulated wave, means for amplifying said resultant wave, means for detecting the amplitude modulation envelope of said complex wave, means for amplifying said detected envelope, and means for amplitude

modulating the amplified resultant wave with the amplified detected modulation envelope.

4. In a transmitter, means for generating a complex wave which is amplitude modulated and phase modulated by intelligence to be transmitted, a limiter coupled to receive a portion of the output of said generating means to provide a resultant phase modulated wave at the limiter output, a nonlinear amplifier coupled to the limiter output, an amplitude modulation detector coupled to receive the remaining portion of the output of said generating means, a linear amplifier coupled to the output of said detector, and an amplitude modulator coupled to the output of said linear amplifier and to the output of said nonlinear amplifier to amplitude modulate the amplified resultant phase modulated wave with the amplified detected amplitude modulations.

5. In a transmitter, means for generating a complex wave which is amplitude modulated and phase modulated by intelligence to be transmitted, means for substantially eliminating amplitude variations from said complex wave to provide a resultant phase modulated wave, means for amplifying said resultant wave, means for detecting the amplitude modulation envelope of said complex wave, means for amplifying said detected envelope, means for effecting a predetermined time delay of the amplified detected amplitude modulation envelope, and means for amplitude modulating the amplified resultant wave with the amplified delayed detected modulation envelope.

6. In a transmitter, means for generating a complex wave which is amplitude modulated and phase modulated by intelligence to be transmitted, means for eliminating amplitude variations from said complex wave to provide a resultant phase modulated wave, means for amplifying said resultant wave, means for detecting the amplitude modulations on said complex wave, means for amplifying said amplitude modulations, means for amplitude modulating the amplified resultant wave with the amplified detected amplitude modulations to provide an output wave, and means for controlling the average power of said output wave in accordance with the energy level of said amplitude modulations.

7. In a transmitter, means for generating a complex wave which is amplitude modulated and phase modulated by intelligence to be transmitted, means for eliminating amplitude variations from said complex wave to provide a resultant phase modulated wave, means for nonlinearly amplifying said resultant wave, means for detecting the amplitude modulation envelope of said complex wave, separate means for linearly amplifying the detected envelope, means for amplitude modulating at a high level the amplified resultant wave with the amplified detected modulation envelope, and means for linearly amplifying the modulated wave output of said last-named means.

8. In a transmitter, means for generating a complex wave which is amplitude modulated and phase modulated by intelligence to be transmitted, means for eliminating amplitude variations from said complex wave to provide a resultant phase modulated wave, means for nonlinearly amplifying said resultant wave, means for detecting the amplitude modulation envelope of said complex wave, separate means for linearly amplifying the detected envelope, means for effecting a predetermined time delay of the

amplified detected modulation envelope, means for amplitude modulating at a high level the amplified resultant wave with the amplified delayed detected modulation envelope, and means for linearly amplifying the modulated wave output of said last-named means.

9. In a transmitter, means for generating a complex wave which is amplitude modulated and phase modulated by intelligence to be transmitted, means for eliminating amplitude variations from said complex wave to provide a resultant phase modulated wave, means for amplifying said resultant wave, means for detecting the amplitude modulation envelope of said complex wave, means for amplifying the detected envelope, means for amplitude modulating at a high level the amplified resultant wave with the amplified detected modulation envelope to provide an output wave, and means for radiating a wave representative of said output wave.

10. In a transmitter, means for generating a complex wave which is amplitude modulated and phase modulated by intelligence to be transmitted, means for eliminating amplitude variations from said complex wave to provide a resultant phase modulated wave, means for amplifying said resultant wave, means for detecting the amplitude modulation envelope of said complex wave, means for amplifying the detected envelope, means for amplitude modulating the amplified resultant wave with the amplified detected modulation envelope to provide an output wave, and means, coupled to the output of said detecting means and operating on said amplitude modulating means, for controlling the average power of said output wave in accordance with the energy level of said detected modulation envelope.

11. In a transmitter, means for generating a complex wave which is amplitude modulated and phase modulated by intelligence to be transmitted, means for separating said wave into its amplitude modulation and phase modulation components and for deriving the amplitude modulation envelope from said wave, means for dividing in frequency the phase modulation component, means for amplifying and for multiplying in frequency the divided-frequency phase modulation component, and means for combining the amplitude modulation envelope of said complex wave with the amplified frequency-multiplied output of said dividing means to provide a resultant amplitude modulated and phase modulated wave representative of said complex wave.

12. In a transmitter, means for generating a complex wave which is amplitude modulated and phase modulated by intelligence to be transmitted, means for separating said wave into its amplitude modulation and phase modulation components, for deriving the amplitude modulation envelope from said wave and for applying such components to separate corresponding channels, means in the phase modulation channel for dividing in frequency the phase modulation component, means for amplifying and for multiplying in frequency the divided-frequency phase modulation component, means in one channel for equalizing the time delays of the signals passing through the two channels, and means coupled to both channels for combining the amplitude modulation envelope of said complex wave with the amplified frequency-multiplied output of said dividing means to provide a resultant amplitude modulated and phase

modulated wave representative of said complex wave.

13. A transmitter according to claim 12, wherein said time delay equalizing means comprises a delay network in the amplitude modulation channel.

14. In a transmitter, means for generating a complex wave which is amplitude modulated and phase modulated by intelligence to be transmitted, means for separating said wave into its amplitude modulation and phase modulation components and for deriving the amplitude modulation envelope from said wave, means for dividing in frequency by the factor n the phase modulation component, means for amplifying and for multiplying in frequency by the factor n the divided-frequency phase modulation component, and means for combining the amplitude modulation envelope of said complex wave with the amplified frequency-multiplied output of said dividing means to provide a resultant amplitude modulated and phase modulated wave representative of said complex wave.

15. In a transmitter, means for generating a complex wave which is amplitude modulated and phase modulated by intelligence to be transmitted, means for separating said wave into its amplitude modulation and phase modulation components and for deriving the amplitude modulation envelope from said wave, a frequency multiplier, means for dividing in frequency the phase modulation component and for thereafter applying the same to said frequency multiplier, to thereby obtain at the output of said multiplier a modulation index equal to that at the input of said dividing means, and means for combining the amplitude modulation envelope of said complex wave with the phase modulation component appearing at the output of said multiplier to provide a resultant amplitude modulated and phase modulated wave representative of said complex wave.

16. In a transmitter, means for generating a complex wave which is amplitude modulated and phase modulated by intelligence to be transmitted, means for separating said wave into its amplitude modulation and phase modulation components and for deriving the amplitude modulation envelope from said wave, means for dividing in frequency the phase modulation component, means for heterodyning the divided-frequency phase modulation component to a different frequency, means for amplifying and for multiplying in frequency the output of said heterodyning means, and means for combining the amplitude modulation envelope of said complex wave with the amplified frequency-multiplied output of said heterodyning means to provide a resultant amplitude modulated and phase modulated wave representative of said complex wave.

17. In a transmitter, means for generating a complex wave which is amplitude modulated and phase modulated by intelligence to be transmitted, means for separating said wave into its amplitude modulation and phase modulation components, for deriving the amplitude modulation envelope from said wave and for applying such components to separate corresponding channels, means in the phase modulation channel for dividing in frequency the phase modulation component, means for heterodyning the divided-frequency phase modulation component to a different frequency, means in the phase modulation channel for amplifying and for mul-

tiplying in frequency the output of said heterodyning means, means in one channel for equalizing the time delays of the signals passing through the two channels, and means coupled to both channels for combining the amplitude modulation envelope of said complex wave with the amplified frequency-multiplied output of said heterodyning means to provide a resultant amplitude modulated and phase modulated wave representative of said complex wave.

18. In a transmitter, means for generating a complex wave which is amplitude modulated and phase modulated by intelligence to be transmitted, means for separating said wave into its amplitude modulation and phase modulation components and for deriving the amplitude modulation envelope from said wave, means for dividing in frequency by the factor n the phase modulation component, means for heterodyning the divided-frequency phase modulation component to a different frequency, means for amplifying and for multiplying in frequency by the factor n the output of said heterodyning means, and means for combining the amplitude modulation envelope of said complex wave with the amplified frequency-multiplied output of said heterodyning means to provide a resultant amplitude modulated and phase modulated wave representative of said complex wave.

19. In a transmitter, means for generating a complex wave which is amplitude modulated and phase modulated by intelligence to be transmitted, means for separating said wave into its amplitude modulation and phase modulation components, for deriving the amplitude modulation envelope from said wave, and for applying such components to separate corresponding channels, means in the phase modulation channel for dividing in frequency by the factor n the phase modulation component, means for heterodyning the divided-frequency phase modulation component to a different frequency, means for amplifying and for multiplying in frequency by the factor n the output of said heterodyning means, means in one channel for equalizing the time delays of the signals passing through the two channels, and means coupled to both channels for combining the amplitude modulation envelope of said complex wave with the amplified frequency-multiplied output of said heterodyning means to provide a resultant amplitude modulated and phase modulated wave representative of said complex wave.

20. A transmitter according to claim 19, wherein said time delay equalizing means comprises a delay network in the amplitude modulation channel.

21. In a transmitter, means for generating a complex wave which has amplitude modulation and phase modulation components, means for amplifying substantially only said phase modulation component, means coupled to said amplifying means for dividing in frequency the amplified phase modulation component, means for amplifying and for multiplying in frequency the divided-frequency phase modulation component, means for amplifying only the amplitude modulation envelope of said complex wave, and means for combining the amplified modulation envelope with the amplified frequency-multiplied output of said dividing means to provide a resultant amplitude modulated and phase modulated wave representative of said complex wave.

22. In a transmitter, means for generating a complex wave which is amplitude modulated and

phase modulated by intelligence to be transmitted, means for substantially eliminating amplitude variations from said complex wave to provide a resultant phase modulated wave, means for dividing in frequency by the factor n said resultant wave, means for amplifying and for multiplying in frequency by the factor n the divided-frequency resultant wave, means for detecting the amplitude modulation envelope of said complex wave, means for amplifying said detected envelope, and means for amplitude modulating the amplified frequency-multiplied output of said dividing means with the amplified detected modulation envelope.

23. In a transmitter, means for generating a complex wave which has amplitude modulation and phase modulation components, means for applying said wave to two amplifying channels in one of which substantially only the phase modulation component is amplified and in the other of which only the amplitude modulation envelope of said complex wave is amplified, means in the phase modulation channel for dividing in frequency the amplified phase modulation component, means for amplifying and for multiplying in frequency the divided-frequency phase modulation component, means for equalizing the time delays of the signals passing through the two channels, and means coupled to both channels for combining the amplified modulation envelope with the amplified frequency-multiplied output of said dividing means to provide a resultant amplitude modulated and phase modulated wave representative of said complex wave.

24. In a transmitter, means for generating a complex wave which is amplitude modulated and phase modulated by intelligence to be transmitted, a limiter coupled to receive a portion of the output of said generating means to provide a resultant phase modulated wave at the limiter output, means for dividing in frequency said resultant wave, means for heterodyning the dividing-frequency resultant wave to a different frequency, means for amplifying and for multiplying in frequency the output of said heterodyning means, a nonlinear amplifier coupled to the output of said multiplying means, an amplitude modulation detector coupled to receive the remaining portion of the output of said generating means, a linear amplifier coupled to the output of said detector, and an amplitude modulator coupled to the output of said linear amplifier and to the output of said nonlinear amplifier to amplitude modulate the amplified phase modulated wave with the amplified detected amplitude modulation envelope.

25. In a transmitter, means for generating a complex wave which is amplitude modulated and

phase modulated by intelligence to be transmitted, means for substantially eliminating amplitude variations from said complex wave to provide a resultant phase modulated wave, means for dividing in frequency said resultant wave, means for heterodyning the divided-frequency resultant wave to a different frequency, means for amplifying and for multiplying in frequency the output of said heterodyning means, means for detecting the amplitude modulation envelope of said complex wave, means for amplifying said detected envelope, means for effecting a predetermined time delay of the amplified detected modulation envelope, and means for amplitude modulating the amplified frequency-multiplied output of said heterodyning means with the amplified delayed detected modulation envelope.

26. In a transmitter, means for generating a complex wave which is amplitude modulated and phase modulated by intelligence to be transmitted, means for eliminating amplitude variations from said complex wave to provide a resultant phase modulated wave, means for applying said phase modulated wave to a corresponding channel, means for detecting the amplitude modulation envelope of said complex wave and for applying such detected envelope to a separate corresponding channel, means in the phase modulation channel for dividing in frequency the phase modulated wave, means for heterodyning the divided-frequency phase modulated wave to a different frequency, means for amplifying and for multiplying in frequency the output of said heterodyning means, means in one channel for equalizing the time delays of the signals passing through the two channels, means in the amplitude modulation channel for amplifying the detected envelope, means coupled to both channels for amplitude modulating the amplified frequency-multiplied output of said heterodyning means with the amplified detected modulation envelope to provide an output wave, and means, coupled to the output of said detecting means and operating on said amplitude modulation means, for controlling the average power of said output wave in accordance with the energy level of said detected modulation envelope.
